UNITED STATES PATENT OFFICE.

GEORGE C. HAMMANN, OF CINCINNATI, OHIO.

ARCH-SUPPORT.

1,112,005.

Specification of Letters Patent.

Patented Sept. 29, 1914.

Application filed August 7, 1913. Serial No. 783,507.

To all whom it may concern:

Be it known that I, GEORGE C. HAMMANN, a citizen of the United States, and a resident of Cincinnati, in the county of Hamilton and State of Ohio, have invented a certain new and useful Improvement in Arch-Supporters, of which the following is a full, clear, and exact description, reference being had to the accompanying drawings, forming 10 a part of this specification.

My invention relates to a supporter for the arch of the foot, and particularly to one which is adjustable.

The object of my invention is to provide 15 an adjustable arch supporter of light weight, and of a spring, or elasticity, adaptable to the needs of the individual foot for which it is intended.

I have found in practice that it is not 20 always easy for the foot to accustom itself to the use of an arch supporter, and thus supporters which are not immediately adaptable to weak or tender feet are frequently discarded when condition really require 25 their use. I have also found that different degrees of flexibility or elasticity are required; also that the weight is not always thrown upon the arch in the same direction or at the same point, and that therefore adjustability of the point or points of support 30 are extremely desirable and necessary. The height and shape of the arch also vary; and it is important, for all of these reasons, especially when the supporter is new to the 35 foot, that suitable adjustments may be made for the comfort and convenience of the wearer; and my invention is therefore directed to the provision of an arch supporter which the wearer may adjust and adapt to 40 the needs and comfort of his foot in all of the above respects, thus obviating the discomfort and nervous strain of compelling the foot to adapt itself to the supporter.

In the drawings: Figure 1 is a side elevation of my new arch supporter; Fig. 2 is a top view of the same; Fig. 3 is a bottom view; Fig. 4 is a top view of the arch plate.

The numeral 1 indicates the main portion, or arch plate, of my new arch supporter. 50 Said plate is made of heavy leather, which is itself adapted to maintain a certain rigidity of form when properly treated and shaped and, at the same time, to be flexible

under weight. The plate 1 is preferably formed with a lip 2 which is adapted to fit 55 the inside of the arch of the foot. The plate is also provided with perforations 3 adapted to receive screw-headed bolts 4 for the attachment of reinforcing springs 5, 6 and 7, nuts 8 securing the springs to the bottom of 60 the plate.

The springs 5, 6 and 7 are preferably made of a high grade of spring steel and may be of any desired elasticity. In the use of my new arch supporter, only such of the springs 65 are attached to the plate as may be needed for the comfort and convenience of the wearer. Where greater spring or elasticity is desirable only the spring 5 is employed; or the springs 5 and 6, where elasticity coupled 70 with a greater support for the inside of the arch than is afforded by the lip 2 alone, may be very effectively and comfortably used. If it is desired to add additional support evenly under the arch both the 75 springs 5 and 7, which are of substantially the same shape, are attached in substantially parallel positions, as spring 7 is shown in dotted lines in Fig. 3; and where preferred results are obtained by centralizing the sup- 80 port under the arch spring 7 is attached diagonally as shown in full lines in Fig. 3; in either case spring 6 may, or may not, be used as preferred. It will thus be seen that by the use of my new supporter as provided 85 with a suitable series of springs suitable adjustments may be effected to suit all requirements both as to shape and rigidity and as to the location of the supporting point or points. By the attachment of the 90 reinforcing springs in the manner shown these adjustments may be made with great facility without the need of special tools for the purpose.

Having thus described my invention, what 95 I claim as new and desire to secure by Letters Patent, is:

1. An arch supporter comprising a plate adapted to fit under the arch of a foot, a series of reinforcing springs detachably secured to the underside of said plate, and means whereby the points of bearing of said springs on said plate may be altered for adjustment.

2. An arch supporter comprising a plate 105 adapted to fit under the arch of a foot, a

lip on said plate adapted to fit against the inner side of said arch, a series of reinforcing springs detachably secured to the under side of said plate and said lip, and means whereby the points of bearing of said springs on said plate and lip may be altered for adjustment.

In witness whereof I have hereunto set my hand in the presence of two witnesses, this 1st day of August, 1913.

GEORGE C. HAMMANN.
